UNITED STATES PATENT OFFICE.

HARRY BENHAM, OF CHICAGO, ILLINOIS, ASSIGNOR TO CHESTERMAN AND STREETER, INC., OF PHILADELPHIA, PENNSYLVANIA, A CORPORATION OF PENNSYLVANIA.

HERNIAL TRUSS.

1,160,565.

Specification of Letters Patent.

Patented Nov. 16, 1915.

Application filed June 3, 1915. Serial No. 31,861.

To all whom it may concern:

Be it known that I, HARRY BENHAM, a citizen of the United States, residing at Chicago, in the county of Cook, State of Illinois, have invented a new and useful 5 Hernal Truss, of which the following is a specification.

My invention consists of a hernial truss composed of a plurality of springs with 10 which are connected respectively front and rear pads of the truss, an axial joint connecting said springs, a hip extension on the front-pad spring, and a connection for said extension with the rear of the truss, producing 15 superior results in the adjustment, action and wear of the truss, the contacting faces of the springs of the front and rear pads being provided with means integral with the same adapted to interlock at said joint, 20 whereby the springs at the latter are prevented from slipping or shifting, and so changing the adjustment, more particularly of the front pad.

The invention is satisfactorily illustrated 25 in the accompanying drawing, but the important instrumentalities thereof may be varied, as long as they are included in the scope of the claims.

Figure 1 represents a perspective view 30 of a hernial truss embodying my invention. Fig. 2 represents a section of a portion on line $x-x$ Fig. 1. Fig. 3 represents an elevation of the inner face of one of the springs of the truss. Fig. 4 represents an elevation of the inner face of the other spring of the truss. Fig. 5 represents a longitudinal section of a portion of what is shown in Fig. 3, on an enlarged scale. Fig. 6 represents a longitudinal section of a 40 portion of what is shown in Fig. 4, on an enlarged scale.

Similar numerals of reference indicate corresponding parts in the figures.

Referring to the drawings. 1 designates 45 a spring or resilient piece to which is attached the front pad 2, the latter being adapted to press the rupture ring.

3 designates an auxiliary spring or resilient piece to which is attached the back pad 4. The springs 3 and 1 are connected 50 at the side of the truss by the screw 5 which thus forms a pivotal connection and axis of said springs, permitting the latter to be

turned on each other and so be raised and lowered to adjust the pads in position. 55

The spring 1 is continued downwardly from the screw 5 by the piece 6 forming the hip extension of the truss with the lower portion of which said piece 6 is adjustably attachable as at 7, the short elastic strap 8 which extends obliquely therefrom to the back pad 4 with which it is connectible as at 9, it being evident that by proper manipulation of the hip piece 6, the spring 1 particularly may be turned on its axis, whereby 60 the front pad 2 may be adjusted to the rupture ring so as to exert proper pressure thereon without severity, as a great portion of usual pressure is avoided, while the truss may be worn with the greatest comfort. 70 Then the strap 8 is fastened to the hip extension, and so under ordinary circumstances, the pad 2 retains its adjusted position, but as the springs are liable to turn on each other at their axial connection 5 75 and so destroy the adjustment of the springs 1 and 3, I form interlocking means on the inner face of the spring 1 and the inner face of the spring 3 about the place of occupation of the screw 5, said means consisting 80 of projecting teeth 10 on one spring, and depressed serrations or teeth 11 on the other spring centered from the openings in the spring occupied by the screw 5, the teeth 10 being adapted to enter the teeth 11, and 85 so engage especially when the screw is tightened increasing the friction of the joint and so one spring will not slip on the other, but when the screw is loosened the springs separate and the teeth disengage, when the 90 springs may be moved on each other for purposes requiring the same, without interference of the teeth. Attention is also directed to the fact that as the teeth 10 and 11 are on the opposite inner faces of the 95 springs they are covered and concealed and do not present themselves for contact of the hands or garments of the wearer.

Having thus described my invention what I claim as new and desire to secure by Letters Patent, is:—

1. In a truss, a plurality of springs, front and rear pads respectively on said springs, a device adapted to connect said springs and form a pivotal joint therefor, a hip extension of the front spring, a connection for

said extension with the rear of the truss, and toothed members on said springs and integral with the same respectively around said device adapted to interlock controlled by said device.

2. In a truss, a plurality of springs, respectively front and rear pads on said springs, a screw connecting said springs forming an axial joint therefor, a hip extension of the front spring, a connection for

said extension with the rear of the truss, the opposite inner faces of said springs about said connecting screw having thereon teeth integral with the respective springs adapted to interlock controlled by said screw. 15

HARRY BENHAM.
